UNITED STATES PATENT OFFICE.

LOUIS SCHUGERL, OF NEW KENSINGTON, PENNSYLVANIA, ASSIGNOR OF FORTY-EIGHT PER CENT TO BRUNO REGALI AND JOHN REGALI, BOTH OF NEW KENSINGTON, PENNSYLVANIA.

WINDOW-SASH CONSTRUCTION.

Application filed March 27, 1928. Serial No. 265,105.

The present invention relates to improvements in windows and has reference more particularly to a window sash that is adapted for slidable and swingable movement in the window frame.

One of the important objects of the present invention is to provide a window sash construction which includes a means for locking the same against swinging movement, so as to cause the window sash to slide vertically in the frame, means being provided for moving said locking means to an inoperative position, whereby to permit the window sash to be swung on a horizontal pivot for the purpose of reversing the window sash to permit cleaning of both sides of the window pane without necessitating the removing of the sash from the window frame.

It is further unnecessary for the window cleaner to assume a position outside of the window frame.

A still further object is to provide a window sash construction of the above mentioned character, which is simple in construction, strong and durable, inexpensive, and further well adapted to the purpose for which it is designed.

Other objects of the invention will become apparent as the nature of the invention proceeds and when taken in connection with the accompanying drawing.

In the accompanying drawings, forming a part of this application and in which like reference characters designate like parts throughout the several views:

Figure 1 is a front elevation of a window frame provided with my present improvements.

Figure 2 is an enlarged sectional view taken approximately on the line 2-2 of Figure 1.

Figure 3 is an enlarged detail view of one of the window sashes, one of the locking bars being shown in an extended position, a portion of the window sash being shown in section.

Figure 4 is a top plan view of one of the window sashes.

Figure 5 is a fragmentary bottom plan view.

Figure 6 is an edge elevation of the window sash, and

Figure 7 is a detail view of the pivot that

is provided for each side of each window sash.

In the drawings, wherein for the purpose of illustration is shown the preferred embodiment of my invention, the numeral 1 designates generally a window frame, and arranged in the window frame for vertical sliding and horizontally swinging movement are the upper and lower window sashes 2 and 3 respectively. The sides of the window sashes are slidable between the usual blind stops 4, 5, and 6 respectively, that are arranged at the opposite sides of the window frame, these stops being spaced with respect to each other to provide longitudinal channels for a purpose to be presently described. It will be observed from Figure 2 of the drawings that the outer side edges of the window sashes do not enter the channels between the blind stops but engage with the outer side faces thereof.

The inner side rail 7 of each side of the window frame 1 is formed with the longitudinally extending grooves 8, which are disposed in alignment with the channels formed between the spaced blind stop as is also shown very clearly in Figure 2. A pulley 9 is supported within a suitable opening provided within each rail 7, outwardly of each of the longitudinal grooves 8, and a cable 10 is trained over each pulley. A counterweight 11 is secured on the lower end of each cable, for disposition outwardly of the rail 7, which is confined within the hollow sides of the window frame, the other end of each cable being formed with a knot 12, that is secured in the notched upper end of the sleeve 13, arranged in each channel or groove 8, the outer end of each sleeve being formed with an extension 14, at the top thereof, in which the notched end of the respective cable is attached. The purpose of this sleeve will be presently described.

Each side of each sash is formed with a groove 15, that extends for the full length of the sash, this groove extending inwardly from the outer edge to the intermediate portion. A pair of curved slots 16, are formed in the sides of the groove or channel, in each side edge portion of each of the sashes, and these slots are arranged in registration adjacent the upper edge, as more clearly disclosed in Figure 3. If desired a face plate 17 may be secured on the inner face of each

side of each sash, and this face plate is formed with a slot that registers with the aforementioned registering slot.

- Cooperating with each vertical groove or channel 15 is the elongated flat bar 18, the same being of a length less than the length of the slot or groove 15. A bracket 19 is secured to the inner face of the upper end of each of these bars, a similar bracket 20 being secured to the inner face of the lower end of each bar. A plate 21 is secured in a cut-out portion formed in the upper face of the top rail of each window sash, adjacent the respective side edges thereof and the outer end of each plate is formed with a pair of knuckles 22, that cooperate with similar knuckles 23 formed on the upper end of each bracket 19, to receive the connecting links 24, which links are pivoted within the respective knuckles, and provide a means for pivotally connecting the upper end of each bar 18 to the respective plate 21, whereby to permit vertical movement of each bar.
- 25 A plate 25 is secured on the bottom face of the lower rail of each window sash adjacent the respective side edges thereof and the outer edge of each plate 25 is formed with an upwardly disposed portion 26 that extends into the lower end of each channel or groove 15, and a link 27 affords an operative connection between the lower end of each bracket 20 and the upper end of the upwardly extending portion 26 of each of the plates 25.

The lower end of each bracket 19 is formed with downwardly extending lug 28 and extending through the outer end of this lug is a pin 29 that is operable in the registering curved slot 16. A knob or handle 30 is arranged on the inner end of each pin whereby to provide a means for actuating the bar 18 to move the same into or out of the respective channel or groove 15, and as is clearly shown in Figure 3 of the drawings, the bar on one side of the sash 2 is disposed downwardly of the side edge thereof, while the bar that is associated with the other side edge is concealed within the channel provided therefor.

In the intermediate portion of each bar is formed a longitudinal slot 31 to accommodate the sleeve 13 and cooperating with this sleeve is a pintle 32, that extends axially from a bracket 33, secured rigidly to the face portion of each groove or channel 15 and this construction provides a pivotal connection for the window sashes whereby the same may be swung on a horizontal pivot, when the rocking bars 18 are confined within the channels 15 so that a window cleaner can reverse either of the sashes by swinging the same on its horizontal pivot to facilitate cleaning of both sides of the window pane from the inside of the window frame.

When the locking bars 18 are disposed downwardly of the respective sides of each sash, the same will be adapted for slidable movement within the respective channels provided by the blind stops 4, 5, and 6 and the outer faces of these locking bars will engage the inner opposed faces of the side rails 7 of the window frame.

Thus the window sashes will be adapted for vertical slidable movement and cannot swing on a horizontal pivot.

An additional bar 34 is disposed below each of the sleeves 13, the upper end of the bar being secured to the outer end portion of the sleeve by any appropriate fastening means such as is shown at 35, in Figure 7.

It will thus be seen from the foregoing description that I have provided a window sash construction that is capable of either vertical slidable movement or swinging movement in a horizontal plane for the purposes described, and the simplicity of my construction enables the locking bars to be readily and easily actuated for moving into or out of engagement with the respective channels formed in the outer side edges of each window sash.

While I have shown the preferred embodiment of my invention, it is to be understood that minor changes in the size, shape and arrangement of parts may be resorted to, without departing from the spirit of the invention and the scope of the appended claims.

Having thus described my invention, what I claim as new is:

1. A window frame having channels formed in the sides thereof, a window sash for disposition in said frame, the outer side edges of the sash being cut out, a locking bar operable in each cut out portion, means for moving said locking bar outwardly of the respective channel for disposition beyond the side edge of the sash, the outwardly disposed locking bars adapted for disposition in the respective channels to permit the slidable movement of the window sash in the window frame, and means for permitting the swinging of the sash on a horizontal pivot when said bars are disposed within the respective channels in the outer side edges of the sash, said means comprising a pair of sleeves having their outer ends arranged within the respective channels in the sides of the window frame, the inner ends of the sleeves projecting through slots formed in the intermediate portions of the respective locking bars, and pintles secured at the inner ends to the opposite sides of the sash for revolute disposition in the respective sleeves.

2. The combination with a window frame having a guide way, a window sash formed with channels in the outer side edges thereof for the full length of the sash, a pair of locking bars for the respective chan-

nels, said locking bars being of a length less than the length of the respective channels and being pivotally secured at their upper and lower ends, means for moving the channel bars outwardly of the respective channels for disposition beyond the side edges of the sash for engagement within the respective guide ways in the window frame to permit sliding movement of the window sash, said 5 locking bars being of a length less than the length of the respective channels and being pivotally secured at their upper and lower ends, means for moving the channel bars outwardly of the respective channels for disposition beyond the side edges of the sash 30 for engagement within the respective guide ways in the window frame to permit sliding movement of the window sash, and means for permitting swinging movement of the window sash on a horizontal pivot when the 35 locking bars are confined within respective channels, said last mentioned means comprising a sleeve extending into each of the guide ways in the sides of the window frame, the inner end of the sleeve extending through 40 a longitudinal slot formed in each of the locking bars, a bracket rigidly attached to each side of the window sash, and a pintle extending axially from the bracket into the 45 respective sleeve for rotation therein.

10 last mentioned means comprising an inwardly extending lug carried by each locking bar for disposition in the respective channel, the slotted sides of the sash being formed with curved registering slots, a pin 15 extending transversely through the slot and through said slot, and an actuating knob on the outer end of the pin to manually move each of the locking bars into or out of engagement with the respective channels.

15 3. The combination with a window frame having a guide way, a window sash formed with channels in the outer side edges thereof for the full length of the sash, a pair of locking bars for the respective channels, said 20 locking bars being of a length less than the length of the respective channels and being pivotally secured at their upper and lower ends, means for moving the channel bars outwardly of the respective channels for disposition beyond the side edges of the sash 30 for engagement within the respective guide ways in the window frame to permit sliding movement of the window sash, and means for permitting swinging movement of the window sash on a horizontal pivot when the 35 locking bars are confined within respective channels, said last mentioned means comprising a sleeve extending into each of the guide ways in the sides of the window frame, the inner end of the sleeve extending through 40 a longitudinal slot formed in each of the locking bars, a bracket rigidly attached to each side of the window sash, and a pintle extending axially from the bracket into the 45 respective sleeve for rotation therein.

20 3. The combination with a window frame having a guide way, a window sash formed with channels in the outer side edges thereof for the full length of the sash, a pair of locking bars for the respective channels, said 25 locking bars being of a length less than the length of the respective channels and being pivotally secured at their upper and lower ends, means for moving the channel bars outwardly of the respective channels for disposition beyond the side edges of the sash 30 for engagement within the respective guide ways in the window frame to permit sliding movement of the window sash, and means for permitting swinging movement of the window sash on a horizontal pivot when the 35 locking bars are confined within respective channels, said last mentioned means comprising a sleeve extending into each of the guide ways in the sides of the window frame, the inner end of the sleeve extending through 40 a longitudinal slot formed in each of the locking bars, a bracket rigidly attached to each side of the window sash, and a pintle extending axially from the bracket into the 45 respective sleeve for rotation therein.

In testimony whereof I affix my signature.

LOUIS SCHUGERL.
